CHECKING PENCIL

Leland S. Malm and John F. Oneto,
San Francisco, Calif.

Application December 19, 1941, Serial No. 423,650

5 Claims. (Cl. 200—52)

This invention relates to checking pencils which will be found useful in conjunction with suitable electro-magnetic counting systems in the checking of drawings, inventories or the like.

More particularly, the invention relates to a portable checking pencil serving the dual purpose of making a mark on or in relation to the thing counted, and closing a circuit in an associated electro-magnetic counting system to effect a count.

A checking pencil such as that forming the subject matter of this application will be found useful in many operations. For example, in checking blue prints or drawings to determine the total number of such items as electrical outlets or the like, or in the taking of inventories, it will be helpful to have a device capable of not only marking the items counted, but also causing a circuit to be closed to actuate an electro-magnetic counting means. Such electro-magnetic counting means are known in the art and form no part of the subject matter of the present application.

In terms of general inclusion, the objects of this invention are to provide a checking pencil consisting of a holder into which various conventional pencils of the lead propelling type may be inserted to permit marking with the pencil, the said holder also including circuit-making means adapted to be actuated upon the application of pressure to the writing point of the pencil.

Other objects of this invention will become more apparent as this specification proceeds, and the novelty will be pointed out in the appended claims.

In the drawing forming a part hereof:

Figure 1 is a longitudinal section through a checking pencil embodying the principles of this invention; and

Figure 2 is a side elevation of the pencil forming the subject matter of Figure 1.

There is provided an elongated pencil holder in the form of a hollow tubular member 10 adapted to receive for slidable movement therein a conventional lead propelling pencil 11. Since substantially all conventional lead propelling type pencils are of a uniform shape having a tapered end 12, the corresponding end of the tubular member 10 is likewise tapered, as at 13, thus providing a positive stop determining, in one direction, the longitudinal movement of pencil 11 within holder 10. As will be noted from Figure 1, the tapered end 13 of the holder 10 is open, and the tapered portion 12 of the pencil

11 projects therethrough to expose the pencil lead 14.

In many of the conventional lead propelling type pencils, it is necessary to hold one portion against rotation while rotating some other portion to propel or repel the lead. For purposes of illustration, in this application, the portion of the pencil 11 which is to be held against rotation is section 16 of pencil barrel 17. A collar 18 within the holder 10 encircles said section 16 of pencil 11, and a set screw 19, extending through a slot 20 in holder 10, has a threaded engagement with the said collar. Normally set screw 19 is turned completely through the collar to bear against section 16 of pencil 11 and thus hold it against rotation. It is, of course, within the broad principle of this invention that the holder may be modified to meet variances in different pencils by relocating the means just described, or their equivalent, to engage some other part of the pencil which must be retained against rotation in propelling or repelling the lead.

At or about midway of the length of holder 10, we provide a pair of apertures 21 through which the barrel 17 of the pencil 11 may be grasped with the fingers to rotate the same and thus propel or repel the lead 14.

From the foregoing description, it will be understood that pencil 11 is free to move axially in holder 10 within the limits of the restricted movement of set screw 19 in slot 20 in holder 10 and engagement of the tapered portion 12 of pencil 11 by the reduced tapered end 13 of holder 10.

The circuit-making means is retained in the end of holder 10 opposite the tapered end 13, as will be noted from Figure 1. A plunger 24 slidably received within holder 10 is abutted by the end of pencil 11 opposite the tapered end 12, and the said plunger carries a rod 25 extending coaxially of holder 10. The rod 25 on plunger 24 is slidably received for a portion of its length by plug 26, fitted within the end of the holder 10 and having a bore 27 therein in coaxial alignment with the rod 25. Tightly fitted in the outer end of bore 27 in plug 26, there is provided an insulator 29 carrying a contact pin 30. An helical spring 31 disposed between plunger 24 and plug 26 and encircling rod 25 normally urges the pencil 11 toward the opposite end of the holder 10 subject to the combined stop action heretofore described, namely, the restricted end 13 of holder 11 and the movement of set screw 19 in slot 20.

As will be appreciated from Figure 1, pressure 55 on pencil lead 14 will cause axial movement of

pencil 11 within holder 10, against the urge of the helical spring 31 to bring the reduced tip of rod 25 into contact with the pin 30 and thus close a circuit to actuate electro-magnetic counting means. When the mark has been made with pencil lead 14, the holder 10 is raised and spring 31 will urge plunger 24 and pin 25 carried thereby out of operative position ready for further use.

Suitable lead wires 33 and 34 are connected to contact pin 30 and grounded in plug 26, respectively, thus providing electrical connection with any conventional electro-magnetic counting system.

A screw cap 35 has a threaded engagement with the end of the holder 10 as a convenient closure means, and the same is provided with an eye 36 by which the device may be hung, if desired.

From the foregoing, it is believed clear that the invention forming the subject matter of this application may take many forms other than that selected for illustration without departing from the spirit of the invention, and hence full protection is desired according to the scope of the appended claims.

The invention claimed is:

1. A checking device comprising an elongated tubular member having therein a chamber to receive a pencil of a lead propelling type, a closed end and a restricted opening at the other end, an electrical contact fixed in the closed end of the tubular member, a slideable second electrical contact in the tubular member between the end of a pencil received thereby and the fixed contact, yieldable means normally urging apart the said electrical contacts, means carried by the tubular member to hold a part of the pencil against rotation, and an opening in the tubular member providing access to a rotatable part of the pencil.

2. A checking device comprising an elongated tubular member having a chamber therein to slidably receive a pencil of the lead propelling type, a closed end and a restricted opening in the other end, a plug fixed in the closed end of the tubular member, a bore in said plug, an elec-

trical contact seated in the bore of the plug for a portion of its length, a plunger in the tubular member having a contact pin slidably received by the bore in said plug, and a spring member disposed between said plug and said plunger.

3. A checking device comprising an elongated tubular member having a pencil receiving chamber therein, a closed end and a restricted opening in the other end, a plug fixed in the closed end of the tubular member, a bore in said plug, an electrical contact seated in the bore for a portion of its length, a plunger in the tubular member having a contact pin slidably received by the bore in said plug, and a spring member disposed between said plug and said plunger.

4. A checking device of the class described comprising an elongated tubular member having a chamber therein to receive a pencil of the lead propelling type, a collar within the tubular member, a slot in the tubular member overlying the said collar, a set screw extending through the slot in the tubular member and having threaded engagement with the collar, a pair of apertures in the shell of the tubular member permitting gripping of a pencil disposed therein, a pair of electrical contacts disposed in the tubular member; yieldable means normally urging apart the electrical contacts but responsive to pressure applied to the writing point of a pencil carried by said tubular member to permit closing of the contacts.

5. In a checking device, the combination of an elongated tubular holder having a pencil receiving chamber therein, means for retaining a selected part of a pencil received in the holder against rotation, an opening in the holder permitting gripping therethrough of a rotatable portion of the pencil, means limiting axial movement of a pencil within the holder, a pair of electrical contacts disposed in the holder, yieldable means normally urging apart the electrical contacts but responsive to pressure applied to the writing point of a pencil carried by said holder to permit closing of said contacts.

LELAND S. MALM,
JOHN F. ONETO.
